the invention, and to provide an improved refrigerating cabinet particularly adapted for handling trays or molds containing material to be cooled or frozen.

UNITED STATES PATENT OFFICE

2,347,642

REFRIGERATING CABINET

George D. Reinhardt, San Antonio, Tex.

Application September 28, 1940, Serial No. 358,897

11 Claims.

(Cl. 62—101)

This invention relates to new and useful improvements in refrigerating cabinets.

One object of this invention is to provide an improved refrigerating cabinet particularly adapted for handling trays or molds containing material to be cooled or frozen.

Another object of the invention is to provide an improved refrigerating cabinet having means for supporting trays or molds containing material to be refrigerated, and for maintaining said trays or molds in spaced relation, whereby the introduction and removal of said trays into and from the cabinet is facilitated.

Still another object of this invention is to provide an improved refrigerating cabinet wherein the trays or molds are spaced from one another and from the walls of the cabinet so that a proper circulation of the refrigerating medium is assured.

A further object of the invention is to provide an improved refrigerating cabinet having facilities for allowing the trays or molds to drain after their immersion in the refrigerating medium; and wherein there is provided an auxiliary refrigerating compartment separate from the means for supporting the molds.

A still further object of the invention is to provide an improved refrigerating cabinet wherein the refrigerating medium is forced to follow a tortuous path as it flows around the trays or molds; and wherein means are provided for facilitating the removal of trays from the refrigerating zone, whereby jolting and jostling of the trays is avoided.

Still another object of the invention is to provide an improved refrigerating cabinet wherein the refrigerating medium is introduced at one end of the refrigerating zone and withdrawn at the opposite end whereby a maximum of contact between the medium and the trays is obtained; and wherein additional refrigerating medium is introduced intermediate the ends of said refrigerating zone to bolster the hydraulic head of the medium in the intermediate portion of said zone and reduce the fluid level gradient of the medium throughout the refrigerating zone.

A construction designed to carry out the invention will be hereinafter described, together with other features of the invention.

The invention will be more readily understood from a reading of the following specification and by reference to the accompanying drawings, in which an example of the invention is shown, and wherein:

Figure 1 is a plan view of a refrigerating cabi-

net constructed in accordance with the invention. Figure 2 is a longitudinal, vertical, sectional view taken on the line 2—2 of Figure 1. Figure 3 is a vertical, transverse, sectional view taken on the line 3—3 of Figure 1.

Figure 4 is a vertical, transverse, sectional view taken on the line 4—4 of Figure 1.

Figure 5 is a plan view of a refrigerating cabinet constructed in accordance with a modification of the invention.

Figure 6 is a longitudinal, vertical, sectional view taken on the line 6—6 of Figure 5.

Figure 7 is a vertical, transverse, sectional view taken on the line 7—7 of Figure 6.

Figure 8 is a vertical, transverse, sectional view taken on the line 8—8 of Figure 6, and

Figure 9 is a vertical, transverse, sectional view taken on the line 9—9 of Figure 5.

In the drawings, the numeral 10 designates a cabinet suitably constructed so as to contain the apparatus described hereinafter. This cabinet may be made of wood or any desirable material. Located within the cabinet, and spaced therefrom, is a water-tight shell or liner 11 which may be fabricated from metal by welding, or by any other suitable means. The space between the cabinet and the shell is filled with an insulating material 12, and pipes 13 which may be of any desired type are mounted so as to extend longitudinally in the lower and middle portions of the cabinet, being fastened in position by any suitable means (not shown). The upper coils terminate in a header 14 which connects to an accumulator shell 15, while the lower coils lead from a header 16 which connects to the bottom portion of the shell 15. Thus, a circuit is completed through the coils 13 including the shell 15. The liner 11 is filled with a suitable liquid refrigerating medium which may be a salt or calcium chloride brine or any other suitable solution, said liquid being forcibly circulated over the coils 13 and through the interior of the cabinet.

A horizontal support or deck 17 is mounted longitudinally within the upper portion of the cabinet and has one side adjacent the side of the cabinet, and is so situated as to lie beneath the level of the surface of the refrigerating liquid and above the coils 13. The support 17 has longitudinally disposed guide rails 18 welded, or otherwise suitably mounted, on its upper surface, said guide rails serving to guide containers or trays (not shown), containing material to be frozen, along the surface of the support 17 and to keep said trays in alignment thereon. These guide rails constitute longitudinal channels. In addi-

tion, the rails serve to keep the trays spaced from one another so that the refrigerating medium may circulate properly about and through said trays. The support 17 has one end terminating short of the end of the cabinet, so as to leave a space 17' through which the refrigerating liquid may flow in order to maintain circulation of said liquid.

A ramp 18, having substantially the same width as the deck 17, is inclined upwardly from the deck at a point adjacent the space 17'. The ramp 18 projects beyond the end of the cabinet 10, exteriorly thereof, so as to facilitate the insertion and removal of the trays mentioned hereinbefore and is provided with rectangular openings 20 in the lower portion of the ramp 18, said openings lying beneath the surface of the refrigerating liquid and serving to permit the free circulation of said liquid. Additional circular openings 21, formed in the ramp 18, adjacent the openings 20, complement the action of said openings in facilitating the circulation of the refrigerating medium.

A horizontal platform 22 extends outwardly from the outer end of the ramp 18, being supported by suitable braces 23 secured to the cabinet 10. The guide rails 18 extend throughout the length of the ramp 18 and the platform 22. Trays which have been submerged in the refrigerating medium may be placed upon the platform to allow the medium to drain therefrom and flow back into the liner 11.

Vertical guide fins 24 are provided at the end of the deck 17 opposite the end provided with the ramp 18. The fins 24 are in alignment with the guide rails 18 and extend from said rails to the end of the liner 11, as is shown in Figures 1 and 2. Each of the fins 24 is provided with a central opening 25 to allow the circulation of the refrigerating liquid. A buffer plate 26, having a semi-circular cross-section, is secured to the end of the liner adjacent the fins 24, and extends transversely of said liner. The buffer plate 26 serves to space the trays from the end of the liner so that the refrigerating liquid circulates freely on all sides of said trays.

Adjacent the support or deck 17, and longitudinally disposed between one longitudinal side thereof and the side of the cabinet, is an elongated, horizontal, dry chamber 27. The chamber 27 has its bottom surface in a plane slightly below the bottom of the deck 17 (Figure 3) but is liquid tight so that it constitutes a cold dry chamber. This chamber does not extend the entire length of the cabinet 10, but terminates short of the end of the cabinet. Adjacent the end of said chamber 27, a sump 28 is located (Figure 1). A circulating pump 29 is vertically mounted in the sump for the purpose of circulating the refrigerating liquid, and consists of a plurality of propeller blades 30 mounted on a shaft 31, which shaft may be rotated by any suitable means such as an electric motor 32, as shown in Figure 4. The propeller blades 30 are rotatable within a collar 33 and, as shown, are arranged so as to force or direct the cooling liquid in a downward direction.

Between the pump 29 and the end of the cabinet 10 is mounted an elongate, cylindrical, accumulator shell 15. This shell is similar to the type of shell which has been described in detail in my Patent No. 2,117,506, dated May 17, 1938, and will not be described herein. Any suitable similar type of accumulator shell may be utilized. The shell serves in circulating the refrigerating liquid

through the coils 13. A vertical shield plate 15' is positioned upon the deck 17 so as to enclose the shell 15 and prevent the refrigerating liquid from passing downwardly about said shell.

The cabinet is simple in its operation. The pump 29 positively circulates the refrigerating liquid over the coils 13, up through the openings 20 and 21, and along the deck 17 so as to refrigerate the contents of the trays placed thereupon. The trays are spaced from one another and from the walls of the liner 11 by the guide rails 18 and the buffer plate 26, so that a proper circulation of the refrigerating medium among and around said trays is assured. Material which has been removed from the trays may be placed in the dry chamber 27 for further refrigeration.

In Figures 5, 6, 7 and 8 of the drawings, there is shown a modification of the invention. In this form of the invention, there is provided the cabinet 10, the liner 11, and the insulation 12 of the first form, described hereinbefore. In addition, the modified form of the invention includes the coils 13, the header 14, and the accumulator shell 15. A horizontal support or deck 34 is mounted longitudinally within the upper portion of the cabinet 10, and is so situated as to be beneath the level of the refrigerating liquid and above the coils 13. The deck 34 is adapted to receive containers or trays (not shown) containing material to be refrigerated. The level of the refrigerating liquid is shown by a dotted line in Figures 6 and 7 of the drawings.

The deck 34 extends completely across the cabinet 10, and from the left-hand end of said cabinet to a point spaced from the right-hand end thereof. An elongate, rectangular opening 35 is provided in the deck at the left-hand end thereof. A smaller opening 36 is provided in the deck at a point intermediate its ends and near one side thereof, said point being nearer to the right-hand end than to the left-hand end of the cabinet.

The accumulator shell 15 is positioned at the right end of the cabinet 10 in the space between the end of the cabinet and the deck 34. A sump 37 and a pump 38, similar to the sump 28 and the pump 29, described in the first form of this invention, are also positioned between the deck 34 and the right-hand end of the cabinet. The pump includes a plurality of propeller blades 39 mounted on a shaft 40, which shaft may be rotated by any suitable means, such as an electric motor 41 (Figure 6).

A vertical partition 42 extends transversely of the cabinet at the right-hand end of the deck 34, and separates the deck from the accumulator shell 15 and the sump 37. A rectangular opening 43, formed in the partition 42, allows the refrigerating liquid to flow from the deck into said sump. A second vertical partition 44 separates the sump from the accumulator shell. Thus, the refrigerating liquid is forced by the pump 38 to flow in a left-hand direction over the coils 13, up through the openings 35 and 36, and along the deck 34 in a right-hand direction. From the deck, the liquid flows through the opening 43 in the partition 42 and into the sump 37, to be picked up by the pump 38. It will be noted in the drawings (Figure 5), that the opening 35 is considerably larger than the opening 36, so that the majority of the refrigerating liquid flows through the former opening. If the opening 36 were omitted, there would be a considerable gradient in liquid level between the left-hand end and the right-hand end of the cabinet. This is a condition which is not impractical, but is unde-

sirable due to the possibility of the refrigerating liquid flowing over the top of the trays and contaminating the contents thereof. Since, due to the action of the pump 38, there is a hydrodynamic head between the refrigerating liquid below the deck 34 and the liquid above said deck, a sizable stream will flow through the opening 36. This stream bolsters the quantity of liquid present at this point, and reduces the fluid level gradient between the two ends of the deck, whereby said fluid level more nearly approximates a horizontal plane.

Several types of baffles are employed in this form of the invention to cause the refrigerating liquid to follow a tortuous path, whereby the trays are efficiently cooled by the refrigerating liquid. A plurality of spaced, vertical baffles 45 extend transversely of the cabinet above the deck 34 throughout its length. Each of the baffles 45 has its lower edge secured to the deck by some suitable means, and has one end secured to one side of the cabinet. The baffles project above the housing, and may, if desired, have their corners rounded (Figures 7 and 8) for reasons of safety. The baffles extend to a point spaced from the other side of the cabinet, and have their lower corners, adjacent the deck, provided with rectangular openings or notches 46. The notches 46 provide additional flowing space for the refrigerating liquid, while the larger upper portion of the baffles tend to maintain the surface of the liquid relatively free of eddies.

The containers or trays (not shown) are placed between the baffles 45 for cooling. A pair of semi-circular, flat bumper disks 47 are secured to each side of each of the baffles. The disks 47 are mounted vertically, and are spaced from one another so that the trays are prevented from contacting the baffles directly. This feature insures the correct placing of the trays, so that proper circulation is had on all sides of said trays.

One of the baffles 45 extends completely across the deck 34. This baffle overlies the opening 36 and is identified in the drawings by the numeral 48. The baffle 48 is provided with notches 49, similar to the notches 46, and bumper disks 50, similar to the disks 47. The baffle 48 causes the refrigerating liquid to change its direction of flow as will be hereinafter described.

A plurality of flat, vertical, triangularly-shaped baffles 51 are secured to the deck 34 in the space between the outer ends of the baffles 45 and the side of the cabinet 10, at the right-hand end thereof. As will be noted in Figure 5 of the drawings, the baffles 51 are placed at an angle of approximately 45° with respect to the side of the cabinet, so that liquid flowing transversely of the cabinet between the baffles 45, and toward said side, will be deflected toward a longitudinal path. Additional baffles 52, similar to the baffles 51, are placed at an angle of approximately 90° with respect to the baffles 51 so that the liquid deflected longitudinally by the baffles 51 will be directed back between the baffles 45, as is shown by the arrows in Figure 5. In this manner, the refrigerating liquid is caused to take a transverse path as it emerges from the opening 36, and is turned through 180° so that its path is reversed as it flows down the deck 34. Upon reaching the baffle 48, the liquid is again caused to reverse its path and is augmented by the liquid flowing upwardly through the opening 36. Further baffles 53, similar to the baffles 51, and placed at a similar angle, direct the liquid to-

ward the sump 37 as said liquid emerges from between the last few baffles 45. By means of the various baffles, hereinbefore set forth, the refrigerating liquid is caused to follow a tortuous path as it flows from one end to the other of the deck 34, whereby the trays are thoroughly and efficiently cooled by the liquid and the formation of stagnant spots or eddies is prevented.

An elongate drain sheet 54 extends throughout the length of the deck 34, and is secured to the side of the cabinet above the liner 11. The sheet 54 has its outer edge curved upwardly, and its inner edge curved downwardly, whereby trays may be placed thereupon to drain and the drained liquid caused to return to the deck 34. If desired, the sheet may have a transverse trough 55 formed near one end so as to facilitate the return of drained liquid to the deck. An arcuate wire member 56 (Figure 7) extends upwardly from the deck to the inner edge of the sheet 54 between each pair of baffles 45. The members 56 serve to guide the trays as they are placed upon the deck and removed therefrom, and prevent the trays from catching beneath the edge of the sheet 54 as they are being removed.

In each of these two forms of the invention, there is provided a refrigerating cabinet which assures the correct placing of the trays containing material to be refrigerated, and provides proper circulation of the refrigerating liquid.

Various changes, alterations, and modifications may be made in the size, shape, and arrangement of the herein described elements within the scope of the appended claims.

What I claim and desire to secure by Letters Patent is:

1. A heat exchange cabinet including, an elongate outer casing, a longitudinal deck disposed within the upper portion of the casing and having a plurality of longitudinal channels to receive the articles to undergo heat exchange, means for circulating a heat exchanging liquid within the casing below and above the deck and along said channels in intimate contact with the articles supported thereon, said channels being spaced from each other, a heat exchanging apparatus within the casing including a plurality of coils which extend longitudinally within the casing below the deck, and means for admitting a heat exchange agent to said coils.

2. A heat exchange cabinet including, an elongate outer casing, a longitudinal deck disposed within the upper portion of the casing and arranged to receive the articles to undergo heat exchange, openings in said deck to allow the free circulation of a heat exchanging liquid over said deck, means for circulating the heat exchanging liquid within the casing and around the deck into intimate contact with the articles supported thereon, means for spacing said articles from one another and from the walls of the casing whereby the heat exchanging liquid may circulate properly, a heat exchanging apparatus within the casing including a plurality of coils which extend longitudinally within the casing, and means for admitting a heat exchange agent to said coils.

3. A heat exchange cabinet including, an elongate outer casing, a longitudinal deck disposed within the upper portion of the casing and arranged to receive the articles to undergo heat exchange, openings in said deck to allow the free circulation of a heat exchanging liquid over said deck, longitudinal guide rails mounted on the

upper surface of the deck for the purpose of keeping the articles supported on the deck in alignment thereon, means for circulating the heat exchanging liquid within the casing and around the deck into intimate contact with the articles supported thereon, means for spacing the articles from one end wall of said casing to maintain circulation at the adjacent ends of the guides, a heat exchanging apparatus within the casing including a plurality of coils which extend longitudinally within the casing, and means for admitting a heat exchange agent to said coils.

4. A heat exchange cabinet including, an elongate outer casing, a longitudinal deck disposed within the upper portion of the casing and arranged to receive the articles to undergo heat exchange, openings in said deck to allow the free circulation of heat exchanging liquid over said deck, transverse baffles terminating short of one side of the casing mounted on the upper surface of the deck for the purpose of keeping the articles supported on the deck in spaced relation to one another and for causing the heat exchanging liquid to follow a tortuous path, means for circulating the heat exchanging liquid within the casing and around the deck into intimate contact with the articles supported thereon, a heat exchanging apparatus within the casing including a plurality of coils which extend longitudinally within the casing, and means for admitting a heat exchange agent to said coils.

5. A heat exchange cabinet including, an elongate outer casing, a longitudinal deck disposed within the upper portion of the casing and arranged to receive the articles to undergo heat exchange, means for circulating a heat exchanging liquid within the casing and longitudinally under and over the deck in intimate contact with the articles supported thereon, and a dry storage chamber disposed longitudinally of the deck between one side of the deck and the cabinet, said chamber extending above and below the deck, whereby said chamber is subjected to treatment by said liquid.

6. A heat exchange cabinet including, an elongate outer casing, a longitudinal deck disposed within the upper portion of the casing and arranged to receive the articles to undergo heat exchange, openings in said deck to allow the free circulation of a heat exchanging liquid over said deck, means for circulating the heat exchanging liquid within the casing and around the deck into intimate contact with the articles supported thereon, a heat exchanging apparatus within the casing including a plurality of coils which extend longitudinally within the casing, means for admitting a heat exchange agent to said coils, and a temperature treatment chamber disposed between one side of the deck and the cabinet, said chamber being disposed so as to have its lower side beneath the heat exchanging liquid level, whereby said chamber is subjected to treatment by said liquid.

7. A heat exchange cabinet including, an elongate outer casing, a longitudinal deck disposed within the upper portion of the casing and arranged to receive the articles to undergo heat exchange, openings in said deck to allow the free circulation of a heat exchanging liquid over said deck, longitudinal guide rails mounted on the upper surface of the deck for the purpose of keeping the articles supported on the deck in alignment thereon, means for circulating the heat exchanging liquid within the casing and around the deck into intimate contact with the articles sup-

ported thereon, a heat exchanging apparatus within the casing including a plurality of coils which extend longitudinally within the casing, means for admitting a heat exchange agent to said coils, and a temperature treatment chamber disposed between one side of the deck and the cabinet, said chamber being disposed so as to have its lower side beneath the heat exchanging liquid level, whereby the chamber is subjected to treatment by said liquid.

8. A heat exchange cabinet including, an elongate outer casing, a longitudinal deck disposed within the upper portion of the casing and arranged to receive the articles to undergo heat exchange, openings in said deck to allow the free circulation of a heat exchanging liquid over said deck, means for circulating the heat exchanging liquid within the casing and around the deck into intimate contact with the articles supported thereon, means for spacing said articles from one another and from the walls of the casing whereby the heat exchanging liquid may circulate properly, a heat exchanging apparatus within the casing including a plurality of coils which extend longitudinally within the casing, means for admitting a heat exchange agent to said coils, and a temperature treatment chamber disposed between one side of the deck and the cabinet, said chamber being disposed so as to have its lower side beneath the heat exchanging liquid level, whereby said chamber is subjected to treatment by said liquid.

9. A heat exchange cabinet including, an elongate outer casing, a longitudinal deck disposed within the upper portion of the casing and arranged to receive the articles to undergo heat exchange, openings in said deck to allow the free circulation of a heat exchanging liquid over said deck, longitudinal guide rails mounted on the upper surface of the deck for the purpose of keeping the articles supported on the deck in alignment thereon, means for circulating the heat exchanging liquid within the casing and around the deck into intimate contact with the articles supported thereon, means for spacing the articles from one end wall of said casing to maintain circulation at the adjacent ends of the guides, a heat exchanging apparatus within the casing including a plurality of coils which extend longitudinally within the casing, means for admitting a heat exchange agent to said coils, and a temperature treatment chamber disposed between one side of the deck and the cabinet, said chamber being disposed so as to have its lower side beneath the heat exchanging liquid level, whereby said chamber is subjected to treatment by said liquid.

10. A heat exchange cabinet including, an outer casing adapted to contain a heat exchange liquid, an elongate imperforate deck disposed in the cabinet below the liquid level thereof and having a liquid circulating passageway at one end only, refrigerant means disposed in the cabinet below the deck, elongate transversely spaced channels disposed longitudinally on the deck for progressively receiving articles to undergo heat exchange, and means at the end of the deck opposite to the end having the circulating passageway for displacing the heat exchange liquid from the channels above the deck and discharging such liquid below the deck to cause circulation of the liquid along the channels and in contact with the refrigerant means.

11. A heat exchange cabinet as set forth in claim 10, and a ramp at one end of the deck for feeding articles to the channels.

GEORGE D. REINHARDT.
